[57] CLAIM

The ornamental design for a welder's helmet with sensor-actuated illumination attachment, as shown and described.

DESCRIPTION

FIG. 1 is a front elevational view of a welder's helmet with sensor-actuated illumination attachment showing my new design.

FIG. 2 is a rear elevational view thereof.

FIG. 3 is a side elevational view the opposite side being a mirror image thereof.

FIG. 4 is a top plan view thereof; and

FIG. 5 is a perspective view thereof.
